PROTECTIVE GARMENT

Judith Bottolfsen, Narberth, Pa.

Application November 10, 1949, Serial No. 126,566

4 Claims. (Cl. 2—69)

1

This invention relates to aprons and more particularly to aprons for the use of persons who are bed-ridden or convalescent, and the like.

When a person, particularly a child, is confined to bed due to illness, injuries, or one of many other reasons, there are quite a variety of things they would like to do but are unable to because of the fear of soiling the bedclothes, adjacent floor rugs, patients clothing, etc. For example, when children are recovering from an illness but still confined to bed, painting, pasting and modeling with clay are things that will keep them amused for hours, but also are pastimes that many people refuse a child in bed because of the probability of the bedclothes and numerous other articles being soiled by spilling or dropping of such materials. Also, eating meals in bed presents similar problems because invariably crumbs get on and between the bedclothes and liquids frequently are spilled.

With the foregoing in mind the principal object of the invention is to provide a novel device that can be worn by a person confined to bed and which will effectively protect the bedclothes and other adjacent and surrounding articles from being soiled.

Another object of the invention is to provide a novel device to be worn by a bedridden person which is proof against the leakage of liquids and is constructed to retain liquids and other materials spilled or otherwise deposited thereon.

Another object of the invention is to provide a novel device of the stated character and construction which is not cumbersome and will not hamper ordinary movements of the patient.

A further object of this invention is to provide a novel bed apron having the features set forth which may be used in the care of infants for bathing, changing diapers and the like.

A still further object of this invention is to provide a novel bed apron which may be manufactured easily and cheaply and which may be used repeatedly.

These and other objects of the invention and the various features and details of the construction and use thereof are hereinafter more fully set forth and described with reference to the accompanying drawings, in which:

Fig. 1 is a perspective view showing the bed apron as used on a patient confined to bed;

Fig. 2 is a perspective view showing the bed apron as it may be used on a convalescent patient sitting at a table;

Fig. 3 is a perspective view of the bed apron viewed from the back of the garment portion thereof;

2

Fig. 4 is a perspective view of the bed apron viewed from the front thereof; and

Fig. 5 is a perspective view of a portion of the bed apron showing the means for supporting and stiffening the sides of the apron.

A bed apron 10 made according to the present invention, comprises generally a garment section 11 adapted to be worn by a person and a tray or cover section 12 which is attached to the garment section and designed to overlie and protect the surface of the bed in which such person may be confined. The garment and cover sections of the apron preferably are fabricated of waterproof sheet material such as, for example, one of the many plastic sheet materials now available on the market. The tray or cover section 12 of the apron is provided with upturned edges about its periphery which function to retain in or on the cover section liquids and other materials that may be spilled.

Referring more particularly to the drawings, the garment section 11 of the apron may be secured to the cover section 12 thereof in a suitable manner, for example, for stitching as indicated at 13. Alternatively the garment and cover sections of the apron may be cut from a single continuous piece of sheet material. The garment section 11 comprises a body portion 14 which is adapted to overlie the front and sides of the wearer's body and terminates in its upper part thereof in a pair of oppositely directed arm portions 15. The inner ends of the arm portions 15 at the rearward side of the garment section 11 terminate in relatively free flap portions 16 which extend toward each other and are adapted or arranged to overlie the upper back and shoulder portions of the wearer.

As shown, the flap portions 16 are provided with tie strings 17 by means of which the upper part of the garment, including the arm portions 15 thereof, may be secured in position with respect to the neck and shoulders of the wearer. In addition, the opposite side edges 18 and the garment body portion 14 are provided with loops or the like 19 for receiving tie-strings (not shown) which may be tied together across the wearer's back. It will be apparent that through adjustment of the tie strings 17 and the tie-strings which pass through the loops 19, the garment section 11 of the apron may be made to fit persons within a very wide range of sizes.

The tray or cover section 12 of the apron comprises a flat central portion 20 having continuous upturned edge portions 21 about the periphery thereof. Preferably the central portion 20 of the tray or cover section 12 is of generally rectangu-

lar configuration dimensioned to conform to the length and width of a bed.

Secured at spaced intervals along the upturned edge portions 21 of the tray or cover section 12 are a series of vertically extending tabs or members 22 which are adapted to assist in maintaining the cover section edge walls 21 in the general upstanding relation with respect to the central portion 20 thereof. Each of these members 22 comprises a length of tubular material which may be, for example, the same as that of which the apron is fabricated. The ends of the members 22 are folded over and secured in place by means of stitching or the like so as to form upper and lower projecting loops 23 and 24, respectively. Internally of each member 22 there is inserted a reinforcing rib or element 25, for example, as shown in Fig. 5 of the drawing. Tapes 26 are threaded through the upper loops 23 of the members 22 and the ends of these tapes are tied or otherwise secured to the bed or other suitable structure in the manner and relation shown in Fig. 1 of the drawing so that the tapes are taut and provide a suspension for the vertical edge walls of the cover section 12 which, in collaboration with the reinforcing or stiffening members 25, prevents collapse of the walls and holds them substantially vertical to retain liquids and the like spilled on the tray or cover section 12.

Fig. 2 shows another use of the apron 10. In this case the garment section 11 of the apron 10 is worn by the patient as before and the tray or cover section 12 is employed to protect the top of a card table while the remainder of the tray section 12 rests in protecting relation on the patient's lap. In this instance the tray section 12 is fastened to the card table by tapes going through the lower loop 24 of the member 22, and the stiffening members 25 serve to support and prevent collapse of the upturned edges 21 of the tray portion 12.

From the foregoing it can be seen that this invention provides a novel bed apron which can be worn by a person confined to bed or convalescing which will not hamper ordinary movements of the person and which provides adequate protection for the bedclothes from spilled liquids and other materials.

While certain embodiments of this invention have been illustrated and described herein, it is not intended to limit the invention to such disclosures and changes and modifications may be incorporated and embodied therein within the scope of the following claims.

I claim:

1. A unitary protective apron for bed and convalescent persons composed of flexible waterproof sheet material and comprising a garment section and a cover section extending outwardly from the lower end of the garment section, said garment section having portions to overlie the front and side body portions of the wearer and tubular arm portions to receive the arms of the wearer, said cover section including a flat central portion extending laterally outward and forward of the garment portion and configurated to overlie a generally flat surface of an article of furniture and an upturned wall portion extending continuously about the periphery of said central portion of the cover section and terminating at opposite sides of the garment section, and a plurality of relatively stiff tab members secured in vertically extending relation to the cover section wall portion at predetermined

spaced intervals thereabout and having projecting loop portions formed at least at their upper ends for the passage of securing means, said tab members being resistant to flexure to assist in maintaining the said wall portion in generally upstanding relation to the central portion of the cover section.

2. A unitary protective apron for bed and convalescent persons composed of flexible waterproof sheet material and comprising a garment section and a cover section extending outwardly from the lower end of the garment section, said garment section having portions to overlie the front and side body portions of the wearer and tubular arm portions to receive the arms of the wearer, said cover section including a flat central portion extending laterally outward and forward of the garment portion and configurated to overlie a generally flat surface of an article of furniture and an upturned wall portion extending continuously about the periphery of said central portion of the cover section and terminating at opposite sides of the garment section, a plurality of tab members secured in vertically extending relation to the cover section wall portion at predetermined spaced intervals thereabout and having projecting loop portions formed at least at their upper ends for the passage of securing means, and reinforcing elements resistant to flexure disposed in each tab member and operable to assist in maintaining the said cover section wall portion in generally upstanding relation to the central portion thereof.

3. A unitary protective apron for bed and convalescent persons composed of flexible waterproof sheet material and comprising a garment section and a cover section extending outwardly from the lower end of the garment section, said garment section having portions to overlie the front and side body portions of wearer and tubular arm portions to receive the arms of the wearer, said cover section including a flat central portion extending laterally outward and forward of the garment portion and configurated to overlie a generally flat surface of an article of furniture and an upturned wall portion extending continuously about the periphery of said central portion of the cover section and terminating at opposite sides of the garment section, and a plurality of tab members secured in vertically extending relation to the outer side of the cover section wall portion at predetermined intervals thereabout and forming therewith pockets for the reception of stiffening elements, said tab members each having projecting loop portions formed at least at their upper ends for the passage of securing means.

4. A unitary protective apron for bed and convalescent persons composed of flexible waterproof sheet material and comprising a garment section and a cover section extending outwardly from the lower end of the garment section, said garment section having portions to overlie the front and side body portions of the wearer and tubular arm portions to receive the arms of the wearer, said cover section including a flat central portion extending laterally outward and forward of the garment portion and configurated to overlie a generally flat surface of an article of furniture and an upturned wall portion extending continuously about the periphery of said central portion of the cover section and terminating at opposite sides of the garment section, a plurality of tab members secured in vertically extending relation to the outer side of the cover section

wall portion at predetermined intervals thereabout and forming therewith pockets for the reception of stiffening elements, said tab members each having projecting loop portions formed at least at their upper ends for the passage of securing means, and reinforcing elements resistant to flexure disposed in said pockets and operable to assist in maintaining the cover section wall portion in generally upstanding relation to the central portion of said section.

JUDITH BOTTOLFSEN.
